UNITED STATES PATENT OFFICE.

REDMOND J. TOBIN, OF VALLEJO, CALIFORNIA.

TORCH.

1,370,384.

Specification of Letters Patent.

Patented Mar. 1, 1921.

Application filed December 10, 1918. Serial No. 266,095.

To all whom it may concern:

Be it known that I, REDMOND J. TOBIN, a citizen of the United States, residing at Vallejo, in the county of Solano and State 5 of California, have invented new and useful Improvements in Torches, of which the following is a specification.

This invention has reference to a novel construction of welding or cutting torch, 10 and particularly to torches of the class employing a mixture of oxygen and acetylene to produce the welding or cutting flame.

The principal object of the invention is to produce a torch, the nozzle of which may 15 be moved into different positions without twisting or rotating the handle or hose connected therewith.

Among other features the invention includes means for hingedly securing the nozzle to the head and for rotatably securing said head to the hose carrying stem so that the two joints provide a substantially universal connection between the parts.

The invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the several views, and in which:—

Figure 1 is an elevation with parts in section.

Fig. 2 is a view showing the connection between the nozzle and head.

Fig. 3 is a section on line 3—3 of Fig. 1.

Fig. 4 is a view showing the socket in the head 11.

In these views, 1 indicates the nozzle to which the tip 2 is connected. This nozzle is 45 provided with a cut away part 3 at its rear end, the transverse wall of which is rounded as at 4. A cone shaped projection 5 extends at right angles from said cut away portion of the nozzle, the end of said projection being cylindrical and provided with screw threads, as at 6. An annular groove 7 is formed in the cone shaped part, midway its ends and ports 8 open out into said groove. The inner ends of these ports communicate 55 with the passage 9 which passes through the projection and the body of the nozzle and

opens out into the screw threaded socket 10 formed in the outer end of the nozzle and receiving the tip 2.

The head 11 is provided with the cut 60 away part 12 so that the nozzle may be halved to said head. This part of the head is provided with a cone shaped socket 13, which passes entirely through the head and is adapted to receive the projection 5. When 65 the parts are positioned the screw threaded end 6 will project from the small end of the socket and is adapted to be engaged by the spring washer 14 and the nut 15. In this manner the nozzle is hingedly connected 70 with the head. The cone shaped socket has an annular groove 16 in its wall, which, when the parts are assembled, will register with the groove 7 in the projection. A port 17 opens out into this groove 16 and this 75 port is in communication with the screw threaded socket 18 of the head which receives the shank 19. The other end of this shank is provided with a cone shaped enlargement 20 which engages the cone shaped 80 socket 21 formed in the end of the stem 22. The enlargement is rotatably held in said socket by means of the cup shaped nut 23 on the shank 19 engaging the screw threaded end of the stem. A spring 24 is placed 85 between the nut and a shoulder 25 formed by the enlargement 20. In this way the shank may be rotated in the stem while the spring will keep the joint gas tight.

The transverse wall of the cut away part 90 12 of the head is rounded as at 26 so that the nozzle may be swung in an arc of about 270 degrees. The spring washer will permit this movement of the nozzle while holding the parts gas tight.

It will thus be seen that the torch may be moved into any position by means of the two joints above described. In this way the torch can be used in an over head position without changing the grip or position of the 100 handle, thereby relieving all unnecessary strain on the hand and wrist of the operator.

I desire it to be understood that I may make changes in the construction and in the combination and arrangement of the several 105 parts, provided that such changes fall within the scope of the appended claims.

I claim as my invention:—

1. A torch comprising a shank terminating at one end in a head formed with a 110 conical socket in the side thereof and with an annular groove extending around said

socket, a passage disposed in said shank and opening upon said groove, a nozzle terminating in a head having a conical stud on the side thereof adapted to be seated within 5 said socket and formed with an annular groove extending around the stud in register with said socket groove, a passage disposed in said nozzle and opening upon said stud groove, and means interposed between said 10 socket head and said stud head for resiliently retaining said stud in gas tight engagement in said socket.

2. A torch comprising a stem formed with a conical socket in one end thereof, a passage disposed in said stem and opening into 15 the bottom of said socket, a shank terminating at one end in a conical stud adapted to be seated within said stem socket, said shank being alined with and rotatable relative to 20 said stem, means interposed between said shank and stem for resiliently retaining

said stud within said socket, a head formed on the other end of said shank, said head being formed with a conical socket in the side thereof and with an annular groove 25 extending around said socket, a passage disposed in said shank and opening upon the end of said conical stud and upon said socket groove, a nozzle terminating in a head having a conical stud on the side thereof adapted to be seated within said shank socket and formed with an annular groove extending around the stud in register with said socket groove, a passage disposed in said nozzle and opening upon said nozzle stud groove, 35 and means interposed between said shank socket head and said nozzle stud head for resiliently retaining said nozzle stud in gas tight engagement in said shank socket.

In testimony whereof I affix my signature. 40

REDMOND J. TOBIN.
